CLAIM

The ornamental design for a game ball, as shown and described.

DESCRIPTION

FIG. 1 is a front elevational view of a game ball showing my new design;

FIG. 2 is a rear elevational view thereof;

FIG. 3 is a side elevational view thereof, the side opposite being a mirror image;

FIG. 4 is a front elevational view showing an alternate embodiment of that shown in FIGS. 1, 2 and 3 thereof;

FIG. 5 is a rear elevational view thereof; and

FIG. 6 is a side elevational view thereof, the side opposite being a mirror image.

FIG. 1

FIG. 2

FIG. 3

FIG. 4

FIG. 5

FIG. 6
